UNITED STATES PATENT OFFICE.

CHARLES W. TOCKNELL, OF KENILWORTH, NEW JERSEY.

BOTTLE-HOLDER.

1,301,886.

Specification of Letters Patent. Patented Apr. 29, 1919.

Application filed December 21, 1918. Serial No. 267,813.

To all whom it may concern:

Be it known that I, CHARLES W. TOCKNELL, a citizen of the United States, residing at Kenilworth, in the county of Union and 5 State of New Jersey, have invented a new and useful Bottle-Holder, of which the following is a specification.

This invention relates to a holder for nursing bottles. One of its objects being to provide an elastic supporting device which can 10 be connected to the sides of a baby carriage, chair, or the like and which will hold a bottle in position where it can be grasped readily and at the same time prevented from being thrown aside and broken.

A further object is to provide a device of 15 this character which is simple and inexpensive in construction, can be readily mounted, and cannot cause injury to the child being fed.

With the foregoing and other objects in view which will appear as the description proceeds, the invention consists of certain 20 novel details of construction and combinations of parts which will hereafter be more 25 fully described and pointed out in the claim it being understood that various changes may be made in the construction and arrangement of the parts without departing 30 from the spirit, or sacrificing any of the advantages of the invention as set forth in the appended claim.

In the accompanying drawings the preferred form of the invention has been shown.

35 In said drawings:

Figure 1 is an elevation of the holder, the position of a chair or the like relative thereto and of the supported bottle, being indicated by dotted lines.

Fig. 2 is section on line 2—2, Fig. 1. 40

Fig. 3 is section on line 3—3 Fig. 1.

Fig. 4 is a perspective view of one of the support engaging terminals.

Referring to the figures by characters of reference 1 designates a light coiled spring 45 the ends of which are clamped or otherwise secured within the slit sleeves 2, formed at the inner ends of the hooks 3. A loop 4 is slidably mounted on the spring and engages a ring 5 formed of a coiled spring and which 50 is adapted to slide and to grip firmly upon a bottle B when inserted thereinto.

In using the holder the spring is extended longitudinally and the hooks 3 placed in engagement within the sides of a chair, carriage or other structure indicated at S. The bottle can then be placed in engagement 55 with the ring 5 and will be yieldingly supported by spring 1. As the loop 4 is slide- 60 able on the spring 1, the bottle can be positioned wherever desired.

What is claimed is:

A holder for nursing bottles, comprising support engaging hooks, a coiled spring constituting the sole connection between the 65 hooks, a loop mounted to slide and swing upon the spring, and a bottle gripping ring comprising an endless coiled spring extending through and supported by the loop.

In testimony that I claim the foregoing 70 as my own, I have hereto affixed my signature in the presence of two witnesses.

CHARLES W. TOCKNELL.
